Patented Jan. 10, 1922.

Inventor
M. A. A. FLANNERY.
By *John Flannery Jr.* Attorney

UNITED STATES PATENT OFFICE.

MARY ANN A. FLANNERY, OF FALMOUTH, MAINE.

SPRING HOOK.

1,403,397.

Specification of Letters Patent. Patented Jan. 10, 1922.

Application filed June 19, 1918. Serial No. 240,775.

To all whom it may concern:

Be it known that I, MARY ANN A. FLANNERY, a citizen of the United States, residing at Falmouth, in the county of Cumberland and State of Maine, have invented certain new and useful Improvements in Spring Hooks; and I do hereby declare the following to be a full, clear, and exact description of the invention, such as will enable others skilled in the art to which it appertains to make and use the same.

This invention relates to improvements in spring hooks, and has for one of its objects the provision of a device of this character which is adapted to be secured to a shoe or garment that is provided with an eyelet so that the lacing strings can be caught by the hook instead of passing the same through the eyelet.

Another object of this invention is the provision of a resilient head to the hook adapted to prevent the hook from becoming accidentally detached from the eyelet during use.

A further object of this invention is the provision of a spring hook of the above-stated character, which will be simple, durable and efficient, and which may be manufactured and sold at a comparatively low cost.

With these and other objects in view, as will become more apparent as the description proceeds, the invention consists in certain novel features of construction, combination and arrangement of parts as will be herein-after more fully described and claimed.

For a complete understanding of my invention, reference will be had to the following description and accompanying drawing, in which:

Figure 1 is a front elevation of spring hooks applied to eyelets of a garment or shoe, and which are constructed in accordance with my invention,

Figure 2 is a plan view of the same, illustrating the hook extending through an eyelet and secured to the garment carrying the eyelet.

Figure 3 is a perspective view of the hook.

Referring in detail to the drawing, the numeral 1 indicates as an entirety a hook constructed from a single length of wire, which is bent near one end into circular formation to form an attaching loop or base

2, which can be readily sewed to a garment or shoe, or may be secured thereto in any well known manner. After the formation

of the base or attaching loop 2, the wire is then bent angularly thereto to form a shank 3, the end of which extends forwardly over the base or attaching loop, and is bent upon itself to form a resilient head 4. The end of the wire after forming the head 4 is bent downwardly in close relation to the shank 3 and forwardly to form a finger 5, which cooperates with the base 2 in supporting the hook on a garment or shoe. The hook 1 is adapted to be used in connection with eyelets, as illustrated in Figure 1, by inserting the head 4 through the eyelet, permitting the shank 3 to be positioned directly in the eyelet and the base stitched, or otherwise secured to the under face of the garment, as illustrated in Figure 2 in dotted lines. In order to insert the head 4 through the eyelet it is necessary that the head be compressed, and owing to its resiliency will return to its initial formation after being released to retain the hook within the eyelet. The hooks are to be inserted through the eyelets and can be used in connection with the ordinary lacing strings, as illustrated in Figure 1. However, the hook may be used directly upon garments without having eyelets by attaching the base 2 to the garments by stitching or other fastening means.

While I have shown and described the preferred embodiment of my invention, it will be understood that minor changes in construction, combination and arrangement of parts may be made without departing from the spirit and scope of the invention as claimed.

Having thus described my invention what I claim is:

A spring hook comprising a single length of wire bent adjacent one of its ends to form a circular attaching base and extending upwardly and rearwardly therefrom to form a shank, said wire after forming the shank being bent forwardly in an arc and rearwardly upon itself to form a head, said head being disposed over and in spaced relation to the base, said wire after forming the head being extended downwardly across the shank and forwardly in a plane with and laterally of the base to form a finger grip to contract the head.

In testimony whereof I affix my signature in presence of two witnesses.

MARY ANN A. FLANNERY.

Witnesses:

JOSEPH E. F. CONNOLLY,
MARY D. KEEFE.
